CONCEALED HINGE

Joseph Soss, Roselle, N. J.

Application March 27, 1939, Serial No. 264,347

4 Claims. (Cl. 16—135)

This invention relates to concealed hinges, and particularly to hinges of this type and kind formed from sheet metal butt parts, one comprising a substantially U-shaped housing part, and the other a hook-shaped arm part; and the object of the invention is to provide a hinge of the kind under consideration wherein the hook-shaped butt part is of channelled cross-sectional form, the inner end of the hook-shaped butt being movably supported upon a pintle fixedly arranged in the housing butt part; a further object of the invention consists in providing in the separate butt parts relatively long bearings for arrangement on the pintle pin; a further object of the invention is to provide inwardly offset portions on the opposed walls of the housing butt part at the pintle receiving portion thereof to provide bearing surfaces upon which the pintle end portion of the hook arm is adapted to rest, while at the same time leaving the remainder of the arm free for swinging movement through the housing butt part; a further object being to provide a hook arm of the character described, the outer wall of which is provided with an inwardly offset rib extending throughout the major portion of the length of the arm and through the curved portion thereof to give greater strength and rigidity to said arm, and still further to the reinforcement of that part of each butt where the attaching plate portions of the butt join the top and bottom walls of the housing and hook arm butt parts; and with these and other objects in view, the invention consists in a hinge of the class and for the purpose specified which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a plan and sectional view of one form of hinge which I employ.

Fig. 2 is a broken section substantially on the line 2—2 of Fig. 1.

Fig. 3 is a view similar to Fig. 1 showing only a part of the construction and illustrating a modification; and

Fig. 4 is a broken section on the line 4—4 of Fig. 3, indicating the complete hinge.

In the construction of hinges of the general type and kind under consideration, it has been the practice to provide straight or non-chan-

nelled hook arm portions fixedly pivoted to or movably coupled with the housing butt part, and to simply pass a pintle or pivot pin through the wall structure of the housing part and a long bore or passage at the inner end of the hook arm part. It has also been a custom to use multiple links in coupling the butts of concealed hinges. Contrary to this more or less conventional procedure, I employ a hook arm butt part which is fashioned from sheet metal and of channelled cross-sectional form throughout the major portion of its length. Further, I provide in a butt part of this type relatively long bearings for engagement with the pintle pin, employed either by drawing or extruding the metal from the top and bottom walls inwardly in forming long bearings on the pintle pin, or in curling the inner end of the hook arm butt part to form a long cylindrical bearing extending between said top and bottom walls. Further, my invention consists in drawing or extruding the metal of the top and bottom walls of the housing butt part outwardly to also form long bearings for the reception of the pintle pin to give greater strength and rigidity to the entire hinge and longer wearing life thereto. As a further structural feature, my invention consists in offsetting part of the top and bottom walls of the housing inwardly where the pintle passes therethrough to form bearing surfaces of restricted area for the hook arm butt part, leaving the remainder of the hook arm butt part free to swing relatively to the housing butt part; and still further my invention consists in the reinforcement of each butt part or the top and bottom walls thereof where the attaching plates join said walls.

In Figs. 1 and 2 of the drawing, I have shown one adaptation of the invention and in said figures, 10 represents a housing butt part, and 11 the hook arm butt part, each part being formed from a single sheet metal blank. The housing butt part comprises a channelled or U-shaped butt consisting of a top wall 12, and a bottom wall 13 joined by a connecting wall 14 at the inner end of the butt 10. The forward end of the top and bottom walls have upwardly and downwardly extending attaching plate portions 15 apertured to receive screws or other fastening devices. As will be seen in Fig. 1 of the drawing, the back wall 14 is arranged at a slight angle to the plane of the attaching plates, and one side of the top and bottom walls 12 and 13 is offset as seen at 16 to accommodate the particular hook arm butt part employed. The ex-

tended side 16 at the rear corner portion of the top and bottom plates is offset inwardly to form inwardly projecting bearing surfaces 17. These offset portions are drawn or extruded outwardly 5 as seen at 18 in forming long or relatively thick tubular bearing portions for the pintle pin 19 of the hinge. This pin is preferably knurled or roughened as seen at 19a adjacent the upper head end thereof to retain the pin against accidental displacement from the housing and to prevent rotation of the pin therein. The top and bottom plates 12 and 13 as well as the corner portions of the attaching plates 15 are offset outwardly as seen at 20 to reinforce and 10 strengthen the housing butt part. Two of these reinforcements are preferably arranged on each wall as will be apparent from a consideration of Fig. 1 of the drawing.

The butt part 11 comprises a hook arm portion 21 of channelled cross-sectional form; that is to say, the hook arm comprises an outer wall 22 having upper and lower inwardly extending flanges or wall parts 23 of the general contour illustrated in Fig. 1 of the drawing. These wall parts 25 extend widely where they join the upwardly and downwardly extending attaching plates 24, and are enlarged at the inner pintle ends 25 thereof. The outer wall 22 is also offset inwardly as seen at 22a throughout the major portion of its length to form a reinforcing rib giving strength and rigidity thereto. The enlarged inner end portions 25 of the top and bottom walls of the hook arm are drawn or extruded inwardly to form thick or long bearing portions 30 26, similar to the bearings 18. These bearings are tubular in form to receive the pintle 19 and will provide much longer bearing surfaces on the hook arm longitudinally of the pin, thus giving added strength and rigidity to the entire hinge, as well as insuring greater wearing life thereto. These long bearings will also substantially eliminate the sagging of the hook arm butt part in the housing butt part as will be apparent.

45 The corner portions of the butt 11 where the attaching plates 24 join the top and bottom walls 23 are offset inwardly as seen at 27 to reinforce and strengthen the mounting of the hook arm butt in connection with the door or swinging member; and two of these reinforcements are provided on each top and bottom wall in the construction shown. In this connection it will be understood that in some hinge constructions only one of the hinge reinforcements 20 and 27 50 need be employed. By constructing a hinge in the manner described, it will appear that a very strong hinge can be produced from relatively thin sheet metal. In fact, a hook arm butt part of the channelled cross-sectional form disclosed 55 will produce a very sturdy hook arm portion, and one of greater strength than conventional solid flat plate arms. Further, by corrugating the outer wall of the hook arm, additional strength and rigidity is provided.

60 At 14a is shown a countersunk aperture for the reception of a screw head or the like in providing an additional mounting of the butt 10 in connection with a support. This further attachment may or may not be employed depending upon the particular use or adaptation of the hinge but when employed will provide an added support for the housing part within the door frame.

65 Hinges of the type and kind here under consideration may have unlimited uses, but are de-

signed for use in connection with the hanging of doors of motor vehicles to provide a completely concealed hinge when the door is in closed position. It will, of course, be apparent that the contour of the hinge butts may be modified to adapt the same to different types and kinds of installations.

70 In Figs. 3 and 4 of the drawing, a slight modification of the construction shown in Figs. 1 and 2 is illustrated. This modification consists primarily in dispensing with the inwardly drawn bearing portions 26 and instead of stopping the outer wall 22 of the hook arm butt as at 22b, this end of the outer wall is extended and curled to form a cylindrical pintle bearing 28. This bearing extends the full height of the hook arm portion 29 between opposed surfaces of the top and bottom walls 30 and 31 thereof. With this construction, the housing butt part 10 will be the same as the housing butt part shown in Figs. 1 and 2 of the drawing.

75 Aside from the modification in the construction as described in connection with Figs. 3 and 4, the hook arm butt 29 will be the same as the butt 11 shown in Figs. 1 and 2. From this standpoint repetition of the description of these parts is unessential as it will be clear from the illustration in Figs. 3 and 4 that these butt parts are otherwise of the same construction. For this reason only part of the construction has been 80 illustrated in Fig. 3 of the drawing.

85 It will, of course, be apparent that the pintle 19 will fit snugly in the cylindrical bearing 28 as well as in the apertures formed in the top and bottom walls 30, 31, for the reception of the pin 19. This construction will provide a much longer bearing of the hook arm upon the pintle pin than is provided in the construction shown in Figs. 1 and 2.

90 It will be understood that the outer surfaces of the top and bottom walls of the hook arm butt will fit snugly within the seats or surfaces 17, sufficient clearance being allowed only for the free movement of the butts one with respect to the other. However, said outer surfaces of 95 the top and bottom walls of the hook arm butt will be free from the adjacent inner surfaces of the housing part so as to provide free swinging movement of the butts one with respect to the other.

99 The housing butt may be said to comprise a U-shaped butt part terminating at its end in laterally extending attaching flanges. The attaching flanges of both butts are arranged side by side in parallel relationship when the butts 55 are in closed position. The hook-shaped butt may be properly termed a channelled butt or a channelled hook-shaped arm.

Having fully described my invention, what I claim as new and desire to secure by Letters Patent is:

1. In a concealed hinge of the class described comprising a sheet metal housing butt part and a hook arm butt part with a pintle pin fixedly secured in the housing butt part and engaging the hook arm butt part for pivotally coupling said butts, said housing butt part comprising a U-shaped body having spaced top and bottom walls joined by a vertical connecting wall, laterally extending attaching flanges at the free ends of the top and bottom walls, one corner portion only of the top and bottom walls adjacent one side of the vertical wall extending inwardly to form opposed bearing surfaces of limited area on the inner surfaces of said top and bottom walls to 75

- snugly receive said hook arm butt part, and said inwardly extending corner portions of the top and bottom walls having outwardly extending bearing portions to provide relatively long bearings on a
5 pintle pin arranged therein.
2. In a concealed hinge of the class described comprising a sheet metal housing butt part and a hook arm butt part with a pintle pin secured in the housing butt part and engaging the hook arm
10 butt part for pivotally coupling said butts, said housing butt part comprising a U-shaped body having spaced top and bottom walls joined by a vertical connecting wall, laterally extending attaching flanges at the free ends of the top and
15 bottom walls, said top and bottom walls having inwardly extending portions adjacent the vertical wall to form opposed bearing surfaces for said hook arm butt part of limited area around the pintle pin, the boundaries of said inwardly extending portions extending in at least two directions, at least one of the boundaries being arranged angularly to the vertical wall, and said inwardly extending portions having bearings for receiving the pintle pin of the hinge.
- 20 3. In a concealed hinge of the class described comprising a sheet metal housing butt part and a hook arm butt part with a pintle pin fixedly secured in the housing butt part and engaging the hook arm butt part for pivotally coupling said
25 butts, said housing butt part comprising a U-

shaped body having spaced top and bottom walls joined by a vertical connecting wall, laterally extending attaching flanges at the free ends of the top and bottom walls, and one corner portion only of the top and bottom walls adjacent one side of 5 the vertical wall extending inwardly to form opposed bearing surfaces of limited area on the inner surfaces of said top and bottom walls to snugly receive said hook arm butt part.

4. In a concealed hinge of the class described 10 comprising a sheet metal housing butt part and a hook arm butt part with a pintle pin fixedly secured in the housing butt part and engaging the hook arm butt part for pivotally coupling said butts, said housing butt part comprising a 15 U-shaped body having spaced top and bottom walls joined by a vertical connecting wall, laterally extending attaching flanges at the free ends of the top and bottom walls, one corner portion only of the top and bottom walls adjacent 20 one side of the vertical wall extending inwardly to form opposed bearing surfaces of limited area on the inner surfaces of said top and bottom walls to snugly receive said hook arm butt part, and reinforcing ribs on said top and bottom walls and 25 part of the attaching plates thereof, said ribs extending outwardly with respect to outer surfaces of said walls and along the walls for substantially one-half the length thereof.

JOSEPH SOSS. 30
